US0D1066472S

(12) **United States Design Patent** (10) Patent No.: **US D1,066,472 S**
(45) Date of Patent: ** Mar. 11, 2025

(54) **DEVICE FOR APPLYING CONTACT LENSES**

(71) Applicant: **EASYTEAR S.r.l.**, Rovereto (IT)

(72) Inventor: **Gianfranco Passuello**, Rovereto (IT)

(73) Assignee: **EASYTEAR S.R.L.**, Rovereto (IT)

(**) Term: **15 Years**

(21) Appl. No.: **35/517,663**

(22) Filed: **Mar. 31, 2023**

(80) **Hague Agreement Data**

Int. Filing Date: **Mar. 31, 2023**

Int. Reg. No.: **DM/229783**

Int. Reg. Date: **Mar. 31, 2023**

Int. Reg. Pub. Date: **Jun. 30, 2023**

(51) **LOC (15) Cl.** **16-06**

(52) **U.S. Cl.**

USPC **D16/331**

(58) **Field of Classification Search**

USPC D16/331

CPC A61F 9/00; A61F 9/0061
